DESIGN FOR A METAL LOCKER OR SIMILAR ARTICLE

Carl A. Johnson, Jamestown, N. Y., assignor to
Art Metal Construction Company, Jamestown,
N. Y.

Application June 7, 1934, Serial No. 52,091

Term of patent 7 years

To all whom it may concern:

Be it known that I, Carl A. Johnson, a citizen of the United States, residing at Jamestown, Chautauqua County, State of New York, have invented a new, original, and ornamental Design for a Metal Locker or Similar Article, of which the following is a specification, reference being had to the accompanying drawing, forming a part thereof.

In said drawing:

Fig. 1 is a front perspective view of a metal locker or similar article embodying my design.

Fig. 2 is a fragmentary, vertical section, on an enlarged scale, of the door thereof, on line 2—2, Fig. 1.

Fig. 3 is a horizontal section, on an enlarged scale, of the door, on line 3—3, Fig. 1.

Fig. 4 is a horizontal section of the locker on the plane of line 4—4, Fig. 1.

The characteristic features of my design reside in the front face of the locker body, which is devoid of exposed rivets or analogous securing devices, the door having a plain or flat front face devoid of outwardly projecting ribs, flanges or analogous projections, said door, however, having depressed vertical grooves parallel with and adjacent its opposite edges and extending the full height of the door, and spaced horizontally extending slots having flanges projecting inwardly from the edges thereof, as shown.

I claim:

The ornamental design for a metal locker or similar article, substantially as shown and described.

CARL A. JOHNSON.
